OILER

S Q Ewing, St. Louis, Mo.

Application May 1, 1939, Serial No. 270,985

3 Claims. (Cl. 221—52)

My invention relates to improvements in oilers or oil cans and the main object is to provide a device embodying a container or can for the oil, a spout and means for compressing air in the container to eject the oil forcibly from the container through the spout and allow the convenient and safe oiling of machinery without elevating the can over the part being oiled.

Another object is to provide a device of this kind in a simple and convenient form comprising an oil can, an air pump connected to the can, a handle adjacent the pump, a spout having a ball and socket connection to the can, a valve controlling the flow of oil to the spout, and a thumb lever adjacent the handle controlling the said valve.

A further object is to provide a novel pump and handle assembly for an oiler of this kind in which the plunger actuating arm of the pump is slidably associated with the handle for their mutual support and to place the arm in convenient position for use.

With these and other objects in view the invention resides in the novel construction and arrangement of parts as hereinafter fully set forth and claimed, reference being had to the accompanying drawing wherein:

Figure 1 is a side elevation, partly in section, of my oiler.

Figure 2 is a section along the line 2—2 in Figure 1.

Figure 3 is an enlarged sectional detail view of the ball and socket.

Figure 4 is an enlarged section along the line 4—4 in Figure 1.

Figure 5 is an enlarged section along the line 5—5 in Figure 1.

Referring now with more particularity to the drawing my invention comprises an oil can or container 6 of any desired size and material having the wall 7, bottom 8 and top 9, the latter having a cap 10 which when removed permits the filling of the can with oil. The can 6 is not circular in plan or cross section but as shown in Figure 2 is of ovoidal shape having the large round back portion 11 and relatively sharp front portion 12.

A handle 13 is secured by rivets or other suitable means at 14 to the upper back portion of the can and from that point is bent outward and then downward forming a leg 15 extended parallel and spaced outwardly or rearwardly from the can. This handle 13 is formed up from a strip of metal the edges 16 of which are turned

inwardly for stiffening and to provide channels or guides 17.

An air pump 18 including the bottom cap or head 19 and upper cap 20 is mounted alongside the back of the can 6 by a threaded nipple 21 on the cap 19 which is screwed at 22 into the can. A channel 23 connects the nipple with the pump cylinder 24 and a conventional ball check valve 25 is provided in the channel opening toward the inlet of the channel into the can. The pump plunger or piston 26 is slidably mounted in the cylinder 24 and has its operating rod 27 extended slidably up through the cap 20. An expansion coil spring 28 is coiled around the rod 27 and braced between the cap 20 and the plunger 26 normally urges the same downwardly as shown. An operating arm 29 is secured to the upper exposed end of the operating rod 27 by nuts 30 and extends outwardly or rearwardly to the leg 15 of the handle 13. Like this handle 20 the arm 29 is formed up from strip metal folded inward at its edges but these folds are cut away at 31 toward the outer end of the arm to provide a guide ear 32 which is adapted to enter between the folded edges 16 of the handle leg 15 and is upset to form projections or teats 33 which ride the channels 17 in the said leg. Thus the leg 15 of the handle acts as a guide for the arm 29 while the two mutually support each other to form a rigid assembly. Of course, the arm 29 normally stands some distance down on the leg 15 so that by raising the arm with the fingers of the hand holding the handle the plunger 26 may be raised in the cylinder 24 and then when released the spring 28 pushes the 35 plunger down forcing air, which is drawn in at 34, down through the check valve 25 into the can 6.

A valve housing or T 35 is mounted in the top 9 near the frontal portion thereof, the said housing having a threaded center extension 36 threaded at 37 in the top for this mounting. A pick up tube 38 extends from the extension 36 down into the can 6 to a point near the bottom 8 and this tube is bent forwardly slightly at 39 45 so that its lower end will rest close into the corner formed by the junction of the "sharp" front 12 of the can and the bottom. By this arrangement the oil may all be drained from the can by slightly tipping the can forwardly as will be 50 understood.

The tube 38 communicates with a central bore 40 in the barrel 41 of the housing 35. This bore is enlarged at its frontal end 42 and a hard rubber bearing 43 is placed in this enlargement and has 55

an aperture 44 communicating with the bore 40. The outer face of this bearing has a rounded or hemispherical recess 45 and the rounded or ball shaped end 46 of the spout 47 is placed in this recess. A cap 48 is screwed on the end of the barrel 41 and has a central aperture 49 beveled off to fit the ball 46 and hold the same in place against the bearing 43. The bore 50 of the spout 47 is widened where it opens through the ball 46 so that in any angular position of the spout the bore 50 will communicate with the bore 40. The other or rear end of this bore 40 is also enlarged and a plug 51 is screwed at 52 in this enlarged end. A valve stem 53 is slidably mounted through the plug 51 and has a valve head 54 at its end engaging the end of the bore 40 under influence of an expansion coil spring 55 braced between the valve head and plug.

A thumb lever 56 is fulcrumed at 57 in a bracket 58 secured to the top 9, the rear end of the lever being turned down alongside the handle 13 in position to be conveniently operated by the thumb of the hand holding this handle. A link 59 then pivotally connects the other end of the lever 56 and the exposed end of the valve stem 53.

In use the can 6 is filled with oil by removing the cap 10 and then the cap is closed tightly and the can grasped by the handle 13. The fingers are then used to raise the arm 29 several times 30 and as it is released the plunger 26 forces air into the can as described. When the pressure in the can is sufficient the thumb lever 56 is depressed pulling on the valve stem 53 and unseating the valve head 54 allowing the oil to flow out through the spout 47 under the influence of the air pressure in the can. Thus it is evidently unnecessary to raise or otherwise manipulate the can itself to oil any machine part.

The spout 47 may be swung to any angle desired and for this purpose a finger yoke 60 is secured 40 to the spout adjacent its ball end 46, the said yoke having the hooked or arcuate wings 61 by which the stem may be readily manipulated.

While I have herein set forth a certain preferred embodiment of my invention, it is understood that I may vary from the same in minor 45

structural details, so as best to construct a practical device for the purpose intended, not departing from the spirit of the invention and within the scope of the appended claims.

I claim:

1. In an oiler, a container, an open handle on the container having a leg extended downwardly substantially parallel with the adjacent container wall, a cylindrical air pump on the container wall in parallelism with the said leg and communicating at its lower end with the container, a spring-set piston and rod in the pump cylinder and adapted on its downward movement to force air into the container, a check valve to hold the air in the container, the piston rod extending 15 slidably up through the upper end of the cylinder, a piston operating arm secured at one end to the upper end of the piston rod, the opposite end of this arm being slidably associated with the said handle leg, and a valve controlled oil delivery spout communicating with the container and through which oil may be forced from the container by compressed air therein.

2. In an oiler embodying a container and an oil delivery spout communicating with same and through which oil may be forced by compressed air, a handle at one side of the container, including a leg extended in axial spaced relation to the adjacent wall of the container, a cylindrical air-pump on the container wall disposed parallel to the handle leg and having a valve controlled air-inlet into the base of the container, a spring-set piston and rod in the cylinder, adapted on its downward movement to force air into the container through said valve controlled inlet, the rod extending slidably up through the upper end of the cylinder, a piston operating arm secured at one end to the upper end of the piston rod, the opposite end of the arm being slidably connected with the said handle leg.

3. In a structure as defined in claim 2, and means for controlling the oil flow through the oil delivery spout, including an operating lever extended adjacent the operating arm of the air pump.
